UNITED STATES PATENT OFFICE.

JAMES H. HALL, OF LEXINGTON, MISSOURI.

CHALKING-MACHINE.

1,273,219.

Specification of Letters Patent.

Patented July 23, 1918.

Application filed November 20, 1916. Serial No. 132,409.

To all whom it may concern:

Be it known that I, JAMES H. HALL, a citizen of the United States, residing at Lexington, in the county of Lafayette and State 5 of Missouri, have invented certain new and useful Improvements in Chalking-Machines, of which the following is a specification.

My invention relates to a chalking machine to coöperate with articles like billiard 10 cues and I particularly aim to provide an article of this class which may be constantly or power driven. The use of this machine enables the billiard or other player to dispense with handling the chalk so that there 15 is slight danger of the chalk being transferred to his clothing, soiling it or presenting an untidy appearance, and also so that the chalking operation may be effected rapidly and as well without the trouble incidental to chalking cues in the usual manner. 20

One specific object of the invention is to provide a chalk holder for connection to an engine shaft for rotation therewith, in combination with a guide device to deflect the cue tip to the center of the chalk held by the holder, and to provide the guide as a substantially horn-shaped member having a laterally extending wall through which 25 fastening means may be passed to facilitate 30 fastening of the horn to the casing.

With the above and additional objects, such as will hereinafter appear, in view, the invention has been embodied in one preferred form as illustrated in accompanying 35 drawings, wherein:

Figure 1 is a longitudinal sectional view taken centrally through my improved machine, but showing the motor in side elevation, and

Fig. 2 is a front end elevation of the machine.

Referring specifically to the drawings, a suitable casing may be used and for instance 45 the hollow substantially rectangular casing as shown in Fig. 1 of the drawings. This casing comprises a bottom wall 3, side walls 4, and end walls 5 and a top wall 6. Within the casing a suitable motor is disposed and 50 it may be an electric motor as shown at 7 and which is fastened as by screws 8 to the wall 3. When the motor used is an electric motor, the feed wires which are shown at 9, are passed through an insulating guide 10 secured to the top wall 6. The main shaft of the engine 7 is designated 11.

On the said shaft 11, I rigidly mount a suitable holder for chalk which may be in the form of a cylindrical block 12 having a depression 13 at one end. The holder has 60 a shank 14 directly secured to shaft 11 and said shank extends from a plate 15 from which extends at right angles clasping or gripping fingers 16. While any of the number of fingers may be provided, yet I preferably use four. The fingers may be of any suitable shape, for instance corrugated as shown in Fig. 1. Also these fingers are of spring metal and have a tendency to grip the chalk rather than to yield or move from 70 the chalk.

At 17 I show a substantially conical shaped horn which is open at the frustum and from which at the plane of the frustum, a short cylindrical wall 18 extends inwardly 75 and which partly houses the chalk and fingers 16. At the base of the horn, a flat laterally extending wall 19 is provided and through this wall fastening means for instance screws 20, may be passed so as to engage the preferred walls 3, 4 or 6.

The operation of the motor is controlled as usual by a suitable switch but before the motor is set in motion, a chalk block like 12 is inserted intermediate the fingers 16. 80 These fingers effectively grip the chalk and hold it so that it turns with the shaft 11 and with the holder. Thus when the cue tip enters the horn 17, the inclined wall thereof will guide the tip into the socket or depression 13 of the chalk and since the chalk revolves, the tip will be effectively chalked. Wall 18 will catch chalk which is loosened from the block and not retained by the cue tip and since the motor 7 in operation causes 85 an eduction of air, such chalk will be expelled from the machine, falling through the horn 17. As a result, the chalk will not enter the machine and interfere with the operation of the motor.

Since merely the preferred embodiment of the invention has been illustrated and described, it is to be understood that changes in the details of construction may be resorted to within its spirit and scope.

I claim:

1. In a chalking machine, comprising a casing, a chalking device within said casing, a horn extending within one end of said casing and attached to the outside thereof, 110 a tube extending from said horn, said chalking device extending within said tube

so that the tube will catch loosened chalk and the tube being disposed in the path of educed air from the means to operate the holder to expel chalk therefrom.

- 5 2. In a chalking device comprising a casing, a motor within the casing, a substantially frusto-conical horn extending within said casing, said horn having a laterally extending wall, means to secure said wall at one end of the casing to serve as a closure therefor, a tube extending inwardly from said horn, a chalking device secured to the motor and extending within said tube so that the tube will catch loosened chalk, and said tube being in the path of educed air from the motor to expel chalk from the machine.
- 10 3. In a chalking device comprising a casing, a source of power within said casing and having a power shaft extending therefrom, means mounted on said shaft serving as a base support for the chalk, corrugated fingers attached to said means and adapted to grip the chalk, and guide means for cues extending within the casing and attached to
- 15
- 20
- 25

one end thereof, said means having a laterally extending tube within which said chalk gripping means extend so that the tube will catch loosened chalk, and the tube being disposed in the path of educed air from the source of power to expel chalk therefrom.

- 20 4. In a chalking device comprising a casing, a source of power within said casing, a chalking device attached thereto, a closure for one end of said casing in the form of a frusto-conical shaped depression, said frusto-conical shaped depression extending within said casing and having a lateral continuation extending inwardly from said depression and into which said chalking means extend so that the tube will catch loosened chalk, and the tube being disposed in the path of educed air from the source of power to expel chalk therefrom.

In testimony whereof I affix my signature 45 in presence of two witnesses.

JAMES H. HALL.
